UNITED STATES PATENT OFFICE

MAX POPPER, OF NEW YORK, N. Y.

VENTILATING STRIP FOR HATS AND THE LIKE

Application filed June 29, 1929. Serial No. 374,802.

This invention is directed to an improvement in and method of constructing self-conforming ventilating sweat bands for hats, caps, and other headwear, in the use of which provision is made for a comfortable fit of the hat, while at the same time affording complete ventilation of the space within the hat above the head.

In providing a self-conforming ventilating sweat band of this character it is important that the ventilating strip so-called be capable of simple and economical production, be integrally provided with means whereby the ventilating strip may be secured as a unitary structure to the sweat band proper, in the assemblage of the latter with the hat; that the relation of the ventilating strip and sweat band be such as to avoid the possibility of the sweat band proper closing the ventilating openings of the ventilating strip during the use of the hat; and that the application of the ventilating strip between the sweat band proper and hat be such as to present a neat and durable appearance.

The primary object of the present invention is a method of making the ventilating strip so that in a single operation the strip made up of a fabric section and a rubber section may be formed to present a unit structure substantially flexible and conformable, with a portion of the width formed of spaced ribs to provide ventilating channels between them, and the remainder of the width of plain, unbroken surface to provide for the connection of the ventilating strip to the sweat band and to the hat.

A further object is the utilization in such method of a fabric strip cut on the bias, whereby the unitary ventilating strip when completed will readily conform to the curvature necessarily assumed by such strip in its application to the sweat band and to the hat, without liability of wrinkling or buckling.

A further object of the invention is the provision of a ventilating strip wherein the ventilating portion is formed by spaced ribs to provide ventilating channels therebetween, the ribs being arranged at different angles with respect to the edge of the strip and relatively parallel throughout the length of the

strip, or at one angle throughout a portion of the strip and a different angle throughout the remainder of the strip, or at varying angles throughout selected portions of the strip, to thereby insure ventilating openings which will afford more and better air admission under different air conditions, thus insuring the maximum ventilating effect.

A further object of the invention is the utilization with the improved ventilating strip and sweat band, of the conventional bead usually employed as a sweat band conforming means, such bead being capable of a variety of positions in connection with the improved ventilating strip.

In carrying out the method of the manufacture of the improved ventilating strip, a section of fabric, preferably of a width to form a number of ventilating strips, with such fabric cut on the bias, is used as a base for the strip.

A sheet of soft, uncured rubber corresponding in surface dimensions with those of the fabric strip, is placed on the fabric strip, and the two parts in superimposed relation placed in a mold and subjected to pressure and a vulcanizing heat. The mold is formed in part with recesses and in part with plain portions, the recessed and plain portions of the mold being duplicated throughout the width of the mold to simultaneously form a plurality of ventilating strips. Under the pressure and heat the rubber flows into the recesses of the mold and intimately unites in a more or less vulcanized relation with the fabric strip. After the parts have been subjected to the heat and pressure of the mold for a sufficient length of time, say approximately ten minutes, the mold is opened, and the section removed. The section of course according to its width may form one or a number of ventilating strips, and where a number of such strips are formed, they are of course to be separated.

The use of the heat and pressure causes a vulcanizing of the rubber sheet to the fabric strip, so that the resultant product, the ventilating strip, is a unitary, substantially rubber member, completely formed for ventilating purposes and for provision of at-

tachment to the sweat band proper and to the hat.

The product produced by the method, while originally made up of two separate parts, 5 is, when completed, an integral, inseparable, and completely formed ventilating strip.

The invention is illustrated in the accompanying drawings, in which:

Figure 1 is a plan view of the fabric section 10 to be used in making up the ventilating strip.

Figure 2 is a face view of the ventilating strip.

Figure 3 is an enlarged section on line 3—3 15 of Figure 2.

Figure 4 is an enlarged section on line 4—4 of Figure 2.

Figure 5 is a broken elevation showing the 20 ventilating strip applied to the sweat band.

Figure 6 is a broken face view of a 25 ventilating band showing a modified arrangement of ventilating openings.

Figure 7 is a similar view showing another arrangement of ventilating openings.

Figure 8 is a broken perspective view of the 30 preferred form of ventilating strip.

Figure 9 is a broken sectional view showing the improved ventilating strip, sweat band proper, and hat in connected relation, 35 a conventional reed being shown in one position.

Figure 10 is a similar view with the reed in another position.

Figure 11 is a broken face view of another 35 form of ventilating strip.

Figure 12 is a broken perspective view of the die member of the mold.

The improved ventilating strip is, as stated, 40 made up of a fabric section 1 and a rubber sheet applied to the fabric section, such sheet 2 being shown in Figures 3 and 4. The die or forming member of the mold has a surface area to accommodate a fabric and a rubber section of sufficient width to form a plurality 45 of ventilating strips in a single operation, though of course the invention contemplates a die and mold which will form one or any number of ventilating strips. The die or forming member of the mold, shown at 3 in 50 Figure 12, is recessed at appropriate intervals, as at 4, to receive a metallic section 5 which has been formed with a plurality of transverse recesses 6, leaving ribs 7 which, when the metallic section is in place, are substantially flush with the plain surface 8 of 55 the mold.

The rubber strip 2 is placed on the forming member, the fabric strip 1 superimposed thereon, and the plain section of the mold 60 (not shown) is closed upon the fabric strip and the mold placed under pressure in the presence of a heat sufficient to vulcanize the rubber. In the vulcanizing process, the rubber will flow and substantially fill the recesses 65 6 in the insert section 5, the rubber of the sec-

tion 2 at the same time intimately uniting with the fabric section 1. Following treatment for a sufficient period, the mold is opened and the ventilating section, shown more particularly in Figures 2 and 8, will have been formed.

As the result of this treatment, the ventilating section is a composite product in that it has a rubber face and a fabric back, but owing to the intimate association of the fabric and rubber during the heat and pressure of the mold, the ventilating strip is, when completed, a unitary product of soft yielding nature, capable of readily conforming to the hat and to the head of the wearer.

By reason of the recesses 6 in the mold section, the ventilating strip is formed throughout a portion of its width with spaced ribs 9, which by reason of their relative arrangement form ventilating channels 10 between them with such channels fully and completely open at the top and bottom. One end of the ribs 9 are in coincidence with one edge of the ventilating strip, the other end of the ribs, however, terminating short of the opposite edge of such ventilating strip. That portion of the strip beyond the ribs is, by reason of the plain surface 8 of the forming section of the mold, plain and unbroken throughout its length. As will later appear, the plain section of the ventilating strip provides the flap whereby the ventilating strip is secured in place to the sweat band proper, and therefore, for the purposes of this description, that part of the ventilating strip providing the ventilating function will be hereinafter termed the ventilating section, while the plain portion of the strip, indicated at 11, will be hereinafter termed the attaching section.

It is to be remembered that the ventilating strip is to be connected to the sweat band proper, and must therefore, when applied, conform to the shape of the interior of the edge of the hat crown, that is, assume a substantially circular outline. If the fabric strip 1 is therefore of ordinary straight fabric, it is apparent that in applying the ventilating strip and sweat band, the fabric strip would buckle or wrinkle, which is to be avoided. As an essential feature of the method, therefore, the fabric strip 1 is of material cut on the bias which, as well understood, permits a convenient curve-conforming position of the completed ventilating strip without objectionable wrinkles or folds.

The ventilating strip is secured to the sweat band proper, indicated at 12, by stitching the edge 13 of such sweat band proper immediately adjacent the line of juncture between the attaching and ventilating sections of the ventilating strip. This line of stitching is indicated at 14 in Figure 5. The ventilating strip is of course secured to the lower edge of the sweat band proper, as

such sweat band is arranged in the hat, and securing the composite sweat band and ventilating strip in place necessitates the turning of the ventilating section of the ventilating strip upwardly between the sweat band proper and the crown 15 of the hat, as indicated in Figure 9. Thus, the ventilating strip is arranged between the sweat band proper and the hat crown, the ribs 9 of the ventilating section bearing against the hat crown. The ventilating channels 10 are thus open throughout their lengths, admitting air to the top of the head between the sweat band proper and the crown of the hat, as indicated by the arrows in Figures 9 and 10.

If the conventional reed is to be used with the improved ventilating strip, such reed, as indicated at 16 in Figure 9, may be applied on the rib side of the ventilating section of the ventilating strip; or if desired to be arranged between the sweat band proper and the ventilating strip, such reed, as indicated at 17 in Figure 10, may be arranged between the attaching section 11 of the ventilating strip and the sweat band, the sweat band, reed, and attaching section being secured together by the same line of stitching.

Where the ventilating strip is used without the bead, as is of course contemplated, the lower edge of the sweat band proper, if not particularly formed, would present an abrupt and uncomfortable edge in line with the lower edge of the ventilating strip. To avoid this, the sweat band proper, or more particularly the lower edge thereof, is beveled or skived off, as at 18, to reduce the extreme lower edge of the sweat band and substantially merge its inner surface into the rounded edge 19 formed by bending the attaching section of the ventilating strip upwardly. There is thus no objectionable edge presented at this point.

Where the reed is employed on the inner side of the ventilating strip, as in Figure 10, this bead will overlie the edge of the sweat band proper, and such edge, as indicated at 20, may be a square edge without objection, though even here the edge of the sweat band may be beveled off, if desired.

In the ordinary formation of the ventilating section of the ventilating strip, the ribs 9 may extend at right angles to the edge of such strip, so that the incoming currents of air are directed more or less vertically. It has been found an advantage, however, to arrange these ribs at other than a vertical position in order to facilitate a more complete air admission, particularly where the air is in motion.

In Figure 6 there is illustrated a construction in which the respective end ribs, here indicated at 21, and the central rib 22 of the ventilating strip are at right angles to the edge of the strip, while the intervening ribs 23 are in two groups, those indicated at 23 on

one side of the central rib 22 being in parallel relation and at an angle other than a right angle to the edge of the strip while those indicated at 24 are also in parallel relation but at an angle opposite that of the ribs 23.

In Figure 7 the ribs, here indicated at 25, are disposed in parallel relation and all at the same inclination with the edge of the ventilating strip. As an alternative suggestion and one not necessary to illustrate, the ribs on the ventilating section of the ventilating strip forward of the transverse median line of the hat crown may be all inclined in the same direction, while those in rear of such median line may be inclined in the reverse direction.

This relative angular relation of the ribs as shown and described is intended to illustrate that the invention contemplates any desired angular relation of the ribs, either in groups or as an entirety, throughout the length of the ventilating strip.

The primary purpose of these angularly related ribs is to facilitate the entrance of the air for ventilating purposes, as where the ribs are inclined in different groups, one group or the other will be in position to facilitate the entrance of the air, no matter from what direction the air may be blowing, thus materially increasing the ventilating effect.

If desired, and as contemplated, the ribs need not be of straight formation from end to end. In Figure 11 is illustrated a form wherein the ribs, indicated at 26, are of somewhat irregular shape longitudinally, that is, of somewhat curved central portion, as indicated at 27, with the upper and lower portions 28 and 29 vertically offset. The ribs may readily be of other irregular shapes without departing from the spirit of this invention.

The important feature of the present invention resides in the provision of a ventilating strip constructed of a fabric back and rubber face, formed as to its ventilating features, and united into one integral whole by a substantial vulcanizing process, together with a simultaneous molding. The ventilating strip thus is a unit product, soft and flexible, and entirely conformable in use. By reason of the attaching section of the unit product, it may be readily and conveniently applied to the sweat band proper, in a manner to prevent any possible separation of the parts and in a manner to insure that the ventilating section will be at all times in proper position for a complete and satisfactory ventilating function.

It will be noted that the forming element of the mold may if desired and preferably be formed with an overflow cavity 30, to take care of excess rubber during the pressure and heat treatment. Also, it is obvious that the rubber element of the ventilating strip,

as applied to the mold, may be in separate sections, or in fact in irregular and different pieces, as during the treatment in the mold such sections or pieces will unite in an integral whole.

It is to be emphasized that the ventilating strip is a hat protective element as well as a ventilating strip. By reason of the character of the materials employed in the construction of the strip, it is apparent that it is impervious to moisture, hence usual perspiration cannot penetrate through the strip and reach the hat, thus avoiding a heretofore unavoidable disadvantage of the usual hat construction.

The ventilating strip is thus a perspiration proof, flexible, conformable, and thoroughly sanitary article, and one readily and easily constructed and applied.

20. What is claimed to be new is:

1. A ventilating strip for hats and the like, having a bias cut fabric backing and a rubber face, the rubber face being provided with integral outstanding ribs, spaced apart to provide ventilating channels.

2. A ventilating strip for hats and the like, including a composite section formed of an inherently-elastic strip and a bias-cut strip inseparably united, the inherently-30 elastic strip being integrally formed on its face with outstanding spaced ribs of less length than the width of the strip.

3. A ventilating strip for hats and the like, including a fabric section of bias cut 35 and a rubber section secured to the fabric section, the rubber section being integrally formed with spaced ribs extending transversely and terminating short of one edge of the strip.

4. A ventilating strip for hats including a composite section including a rubber face and a fabric backing extending throughout the full area of one surface of said rubber face uniform in lengths and widths, ribs 45 ranged transversely in spaced relation on that side of the rubber face opposite the fabric, the ribs extending from one longitudinal edge of the strip to a line short of the opposing edge, that portion of the strip 50 free of ribs being foldable substantially at the line of the ribs to provide a section of fabric and rubber to be secured to the hat-band.

In testimony whereof I affix my signature.

55. MAX POPPER.
